UNITED STATES PATENT OFFICE.

G. W. COATS AND J. RUSSELL, OF SPRINGFIELD, MASSACHUSETTS.

IMPROVEMENT IN MACHINES FOR STICKING CARD-TEETH.

Specification forming part of Letters Patent No. 11,434, dated August 1, 1854.

To all whom it may concern:

Be it known that we, G. W. COATS and JAMES RUSSELL, of Springfield, Massachusetts, have invented certain new and useful Improvements in Machines for Sticking Card-Teeth, of which the following is a full, clear, and exact description, reference being had to the accompanying drawings, making part of this specification, in which—

Figure 1 is a plan; Fig. 2, an end elevation; Fig. 3, a vertical section taken at the line A a of Fig. 1, and looking in the direction of the arrow; Fig. 4, a vertical section in the plane of the axis of the driving-shaft; Fig. 5, a longitudinal and a cross-section of the screw-leader with its two-part nut; Figs. 6, 7, 8, 9, and 10, vertical sections taken severally at the lines B b, C c, D d, E e, and F f of Fig. 1, and Fig. 11 a like section at the line G g of Fig. 1.

The same letters indicate like parts in all the figures.

It is not deemed necessary to describe or represent what are known in card-sticking machines as the "back bender," the "pricker" for pricking the hole in the leather, nor the "cutter" for cutting off the lengths of wire, as these are to be made and applied as in the machines heretofore generally used. In this, as in other machines for sticking card-teeth, the sheet of leather is held by clamps in an inclined carriage, which works up and down between-walls in a main carriage to determine the space between the several rows, the spacing of the teeth in the rows being effected by the horizontal motion of the main carriage back and forth. These motions have heretofore been given by ratchet movements, which are liable to derangements and inaccuracies.

The first part of our invention consists in giving the longitudinal motion to the main carriage for spacing the teeth in each row by means of a screw-leader attached to the carriage and passing through a nut mounted in a box and rotated by cog-gearing, when this is combined with and receives motion from a cog wheel on a shaft having a clutch operated by a cam on the main or driving shaft, to clutch and unclutch another wheel on the same shaft, which gears into two wheels that run loosely on the main shaft and which are alternately clutched to the main shaft, by means of which combination an intermittent spacing

motion is communicated to the carriage without the necessity of a ratchet movement, and by which also the said motion is reversed.

Our invention also consists in combining with the above mode of operating the feed or spacing motion the employment of cams on the main carriage, which at the end of each traverse motion alternately act on a lever connected and combined with and operating a clutch to clutch a cog-wheel on an arbor which carries a worm or its equivalent to communicate motion from the main or driving shaft to a shifting-wheel which operates a lever connected with the double-acting slide-clutch on the main shaft, first, to shift the clutch to liberate the cog-wheel with which it was connected to stop the feed or spacing motion, and after the other required movements have taken place to shift it to engage the other wheel to reverse the feed or spacing motion of the main carriage; and our invention also consists in combining with the above mode of imparting the feed or spacing motion to the main carriage the mode of operating the inner carriage, which holds the leather, to determine the space between the rows at the end of each longitudinal motion of the main carriage by means of a shifting cam, called the "twill-cam," a shifting sector cog-wheel, which in turn communicates motion by cog-wheels and shaft to a feathered cog-wheel, through which slides a shaft mounted on the main carriage, which in turn communicates motion to drums for lifting the second carriage; and our invention also consists in making the nut that operates the screw-leader in two parts, divided by a plane at right angles to the axis of the leader, and so connecting the two parts of the nut by screws passing through elongated slots in one and tapped into the other, so that the two parts of the nut can be turned on each other to adjust the threads to the thread of the leader when either wear or become loose, thereby affording the means of adjustment of the feed-motion, by means of a screw-leader, so important to an accurate spacing of the teeth; and our invention also consists in having the feed-rollers on two arbors provided with cylindrical bosses to keep them apart, in combination with the mounting of these rollers between a pair of half-boxes below the arbor of the lower roller and

a pair above the arbor of the upper roller, no boxes being interposed between the two, the said arbors being prevented from having end-play by means of V-shaped or curved fillets fitted to corresponding grooves in the boxes, by means of which combination and arrangement we are enabled to prevent the rollers from having end-play or chance without the use of end pivots heretofore employed, which are known to be objectionable, from the place they occupy at the ends of the rollers and their liability to wear, and thereby to permit end-play, which renders the feeding of the wire irregular, and hence the card-teeth of unequal lengths; and our invention also consists in mounting the bending-fingers in a sliding top plate independent of and below the slide or carrier of the former around which the teeth are bent, the said carrier being provided with an inclined plane or cam acted upon by a like inclined plane or cam on the top plate which carries the fingers, so that by the back movement of the fingers, after bending and sticking each tooth, the former shall be lifted out of the loop formed by bending the wire before it is drawn back, thus greatly improving and simplifying the machine as heretofore constructed.

In the accompanying drawings, *a* represents the frame, and *b* the main carriage, which moves back and forth horizontally with the lower edge thereof fitted to slide in a V-groove on the platform of the frame. It inclines back from a vertical line and is held down to the groove by a bracket, *c*, which is secured to the platform and fits over the upper edge of the lower bar. On the front face of this main carriage is mounted a second carriage, *d*, provided with clamps *e e* at top and bottom to hold the sheet of leather *f* and fitted to ways *g g* in the main carriage, which admit of its moving up and down and for a short distance longitudinally for the purpose of determining the "twill of the card," as it is termed. The lower edge rests on two hooks, *h h*, suspended by chains or cords to two drums, *i i*, on a horizontal shaft, *j*, mounted in the main carriage, so that by the turning of this shaft the second carriage is drawn up and let down. By the tension of a spring, *k*, the second carriage is forced in one direction against the end of a slide, *l*, at one end of the main carriage, and forced, when required, in the opposite direction by a series of tappets, *m*, on an arbor, *n*, mounted on the main carriage, which tappets act on the face of a bracket, *o*, on the slide *t*. These tappets, from the first to the last of the series, are each in succession of greater radius. The object of the tappets, as stated before, is to determine the twill, and therefore the increased length of each successive tappet must be proportioned to the space between the teeth of each row in the contemplated card, that the teeth in the second row may be in a line between the teeth of the first row, or in any other relative posi-

tion that may be determined by the required twill. The arbor *n*, which carries the tappets, receives motion from a horizontal shaft, *p*, mounted on the main carriage by means of a pair of bevel-wheels, *q*, and in turn imparts motion by means of a worm, *r*, and spur-wheel *s* to the horizontal shaft *j* to lift the second carriage, so that the upward motion to determine the space between the rows of teeth and the horizontal motion to determine the twill is communicated simultaneously by the shaft *p*, which receives an intermittent motion for this purpose from the main shaft *t* by the following means: A continuous motion is imparted by the main shaft *t* to a cam-shaft, *u*, by means of a pair of bevel-wheels, *v v*, and on the shaft *u* is mounted a sector cog-wheel, *w*, and which by its rotation imparts an intermittent motion to a spur-wheel, *x*, on an inclined shaft, *y*, which carries at its lower end a bevel-wheel, *z*, that engages a bevel-wheel, *a'*, feathered on the horizontal shaft *p*, so that the said shaft may be turned by the wheel, and at the same time be free to slide through it, as the main carriage moves back and forth, the hollow arbor of the said bevel-wheel *a'* being fitted to turn in a suitable collar or box in a permanent bracket, *b'*, attached to the frame; but as the cam-shaft *u* makes one entire rotation for every complete operation of sticking a tooth, and the second carriage is only to be shifted at the end of each row of teeth, the sector cog-wheel *w*, which slides on the cam-shaft, is held back so as not to be in gear except at the end of each complete operation of sticking a row of teeth, and then it engages to give the required motion, and is again forced back. This is effected by attaching the sector-wheel by means of a pin in manner well known to mechanicians, with a sliding rod, *c'*, fitted to the inside of the cam-shaft, which is hollow for that purpose. This rod is forced outward by a helical spring within the shaft, carrying with it the sector-wheel, and at the required time it is forced inward to put the sector-wheel in gear by means of the twill-cam *d'* on the main shaft, and adapted to slide thereon, and operated by a rod, *e'*, fitted to the inside of the driving-shaft, which is hollow for that purpose, the cam being attached to this rod by means of a pin passing through a slot in the shaft, and the rod in turn attached in like manner to a sliding collar, *f'*, on the main shaft, which collar embraces one end of a lever, *g'*, by which it is made to slide the cam when required.

The manner of operating this lever will be presently described. The main carriage receives an intermittent longitudinal motion to determine the space between the teeth of the several rows, and first in one direction and then in the reverse. For this purpose it carries a screw-leader, *h'*, permanently attached to it, so as not to turn, by means of brackets at each end, and this screw-leader passes through a rotating nut, *i'*, the hollow arbor of which is

ntted to turn in a suitable box, j' , attached to the frame and accurately fitted to avoid end-play, and as the thread of the nut and the screw-leader are liable to wear and become loose, which would destroy that nice accuracy of spacing so important in good cards. This is remedied by making the nut in two parts, as represented at Fig. 5, divided by a plane at right angles to the axis, and making the contiguous parts with flanges $k' k'$, connected by screws tapped into one, and passing through segmental slots in the other, so that the two parts can be turned on each other, and thereby change the relations of the thread in the two parts to take up what may be termed the "slack" or "wear." This nut on one end carries a bevel-wheel, l' , which is engaged by a corresponding bevel-wheel, m' , on the lower end of a vertical arbor, n' , mounted in a standard, o' , of the frame; and the upper end of this arbor carries another bevel-wheel, p' , which turns loosely thereon, but which can be clutched and unclutched by a sliding spring-clutch, q' , within the arbor, which is made hollow for that purpose, the stem of this clutch extending up above the upper end of the arbor and within reach of a cam, r' , on the main shaft, by which at every rotation of the main shaft the wheel p' is clutched and unclutched to impart the intermittent spacing motion to the main carriage.

It is not only necessary to give an intermittent spacing motion to the main carriage, but it is necessary to suspend this motion at the end of its range of motion to afford time for the other movements, and then to reverse it. For these purposes the clutch-wheel p' on the arbor n' engages two bevel-wheels, $s' s'$, one on each side, that turn freely on the main shaft, so that when one is clutched and the other liberated the carriage will be moved in one direction, and vice versa. This operation is performed by a double sliding clutch, t' , on the main shaft, to which, for convenience and compactness, the cam r' is attached. This clutch, when moved in one direction, clutches one wheel, s' , and liberates the other, and vice versa, for reversing the spacing motion, and when midway between the two liberates both to suspend the spacing motion. For shifting this double acting clutch, it is attached by a pin to the rod e' within the main shaft in the same manner as the twill-cam and sliding collar f' .

To the main carriage are attached two inclined faces or cams, $u' u'$, by means of screws, so that their distance apart can be adjusted to suit the length of rows intended to be stuck. When the main carriage reaches the end of its motion in either direction, one of these cams u' acts on one end of a lever, v' , which draws a rod, w' , jointed to its other end, in one direction, and against the tension of a restoring-spring, x' . This rod carries a wedge, y' , which acts on and forces up a rod, z' , fitted inside of a vertical arbor, a' , and provided with a restoring-spring, f' , at its lower end, and with a clutch,

c^2 , at its upper end, to clutch, when forced up by the wedge, a bevel-wheel, d^2 , which receives motion from the main shaft by a corresponding wheel, e^2 . So soon as this wheel d^2 is clutched it rotates the arbor a^2 , which carries a worm, f^2 , which imparts motion to a spur-wheel, g^2 , on the arbor of what is termed the "shifting" or "reversing" wheel h^2 . This shifting-wheel h^2 consists of two circular and parallel plates, with a space between them to receive the lower end of the lever g' , before described, for operating the sliding collar f' on the main shaft; and each of these plates is provided with two series of pins, i^2 , projecting inward, one series longer than the other, and alternating.

The two faces of the end of the lever g' are properly beveled to be acted upon alternately on opposite sides by the pins i^2 on the shifting-wheel, so that when the wheel d^2 is clutched by the action of any one of the cams u' of the main carriage on the lever v' the shifting-wheel is set in motion, which brings, first, one of the short pins i^2 on one of the plates against the lever g' to move it in one direction to a sufficient distance to slide the double-acting clutch t' midway between the two bevel-wheels $s' s'$, which suspends the spacing motion of the main carriage. This self-same motion of the lever g' shifts the twill-cam d' , so that it acts on the rod C' to operate the second carriage to give the two motions already specified. The shifting-wheel, being still in motion, then brings one of the long pins i^2 to act on the lever g' to carry it still farther in the same direction, to carry the twill-cam beyond and out of the reach of the rod e' to suspend all further action on the second carriage, and to shift the double clutch to the opposite wheel s' to reverse and restart the spacing motion of the main carriage, and so soon as the carriage begins to move the lever v' is liberated, so that the motions of the shifting apparatus are suspended and restored by the several springs. The cam-shaft u carries a sector cog-wheel, j' , which imparts an intermittent feed-motion to the pair of feed-rollers $k^2 k^2$ to feed in the length of wire required at each operation for forming the card-teeth, the shaft of one of these rollers being provided with a pinion, l' , which is engaged by the cogs of the sector-wheel, and both having pinions $m^2 m^2$, that the two may move with equal velocity. The feed-rollers are cylindrical enlargements of their arbors, with grooves in the periphery of the lower one suited to the different sizes of wire required in making various qualities of cards. The arbor of the lower roller lies and turns in two half-boxes, $n^2 n^2$, fitted to two standards, and the upper roller rests on the under roller, and two half-boxes, $o^2 o^2$, are placed above it, and fitted to slide in the same standard, so that there are no boxes between the two arbors. The upper boxes $o^2 o^2$ are provided with rods $p^2 p^2$, which pass down and are secured to plates $q^2 q^2$ below the stand-

ards, with springs r^2 r^2 interposed, which, by their tension, make pressure on the upper roller to grip the wire between it and the lower roller, the arbors of the two rollers being kept apart by the rollers themselves at one end, and two cylindrical bosses, s^2 s^2 , near the other end. To avoid all end-play in these rollers, which is known to be injurious to the wire, and liable to make the feed-motion irregular, and to do this without the necessity of end pivots, which are seriously objectionable, the journals, instead of being cylindrical, as usual, are V-shaped or curved longitudinally, and the boxes in which they run are of a corresponding shape, as represented in the drawings, Fig. 9, so that the pressure applied by the upper boxes effectually prevents end-play. As the wire is fed in by the feed-rollers it passes in front of the doubler or former t^2 of the usual form, and secured vertically in the end of a carrier, u^2 , the other end of which is secured to a cross-bar, v^2 , having two ways, w^2 w^2 , one at each end, and parallel with the carrier and fitted to slide in grooves in a plate, x^2 , attached to and making part of the frame. Two springs, y^2 y^2 , bear on the two ways to hold down the carrier and former, but permit them to be lifted. So soon as the wire has passed in front of the former it is gripped against the former by means of the "crownier" z^2 , as it is termed, and there held during the bending and sticking operation. This crownier is of the usual form, and secured to a carrier, a^2 , fitted to a cap-plate, g^2 , fitted to slide in the plate x^2 , and below the carrier of the former, and properly fitted to slide therein. The rear end of this carrier is bent up, as at b^2 , to receive the action of a sector-cam, c^2 , on the cam-shaft, by which the crownier is withdrawn after the sticking operation, and when the cam, in its revolution, passes off, the operation of gripping being effected by the tension of a spring, d^2 , attached to the carrier a^2 . After the wire has been gripped, and while it is held by the crownier against the face of the former, it is bent around the former and the two ends brought to a parallelism by the action of the two "fingers," e^2 e^2 , as they are termed. These fingers are of the usual form, and secured by temper and adjusting screws in sockets at the ends of two plates, f^2 f^2 , which, between the sockets and the points of their attachment to the cap-plate g^2 , are reduced in size to act as springs laterally on the fingers in the act of bending the wire around the former. This mode is in contradistinction to the old mode, in which the plates carrying the fingers were jointed to the cap-plate with independent springs acting upon them.

The spring finger-plates are, as before stated, attached at one end to a cap-plate, g^2 , adapted to work in ways in the top of the plate x^2 , and just under the carrier of the former, and the rear end of this plate g^2 is adapted, as at h^2 , to receive the action of a cam, i^2 , on the cam-

shaft, and the rear end of the cross-bar v^2 of the carrier u^2 is also formed, as at j^2 , to receive the action of a cam, k^2 , on the cam-shaft, the object of these cams being to force forward the fingers to bend the wires, and then to force the former and fingers together to insert the wire in the leather, and therefore the cam i^2 should be so much in advance of the cam k^2 as to effect the bending of the wire before the other cam k^2 begins to act, and then both act in unison. The tension of the spring which forces the crowner forward should be sufficient to aid in sticking the wire. The former and the fingers are drawn back by springs d^2 and m^2 . Temper-screws n^2 are inserted through projections on each side of the top plate, x^2 , to adjust the extent of lateral play of the fingers.

The cap-plate g^2 , which carries the fingers, is provided with a cam-face or inclined plane, o^2 , just below the carrier of the former, which is also provided with a corresponding cam-face or inclined plane, p^2 , for the purpose of operating the former up and down. The cam which operates the fingers is, as before stated, a little in advance of the cam which operates the former, so that on the return motion the fingers begin their back movement, which causes the cam-face p^2 to act on the cam-face o^2 , to lift the former out of the loop form of the wire after its ends have been stuck into the leather, and so soon as the former is lifted out then the cam permits it to return to its original position for another operation.

Having thus specified the principle or character which distinguishes our invention from all other things before known and described the manner of constructing and using the same, we wish it to be distinctly understood that we do not limit ourselves to the special construction of parts, but claim the privilege of making such changes as are merely formal and embodying the same essential principles or combinations herein specified.

What we claim as our invention, and desire to secure by Letters Patent, is—

1. The mode of imparting the intermittent motion to the main carriage for spacing the teeth, and reversing the same by means of the screw-leader attached to the main carriage, and passing through a nut mounted in suitable boxes, and rotated by cog-gearing, as described, when this is combined with a clutch operated by a cam to clutch or unclutch the wheel which receives motion from the wheel or wheels on the main shaft, and imparts the required and measured intermittent motion to the nut, substantially as and for the purpose specified.

2. In combination with the mode described of imparting the spacing motion to the main carriage, the employment of the cams on the main carriage, which, at the end of each traverse motion, act on a lever connected and combined with and operating the clutch to clutch and unclutch the wheel, which receives motion

from the main shaft to operate the shifting-wheel, which operates the double clutch on the main shaft, substantially as and for the purpose specified.

3. In combination with the mode described of operating the main carriage, the mode of operating the second carriage, which holds the sheet of leather, to determine the space between the rows of teeth, by means of the shifting-cam, called the "twill-cam," and the shifting sector cog-wheel, which in turn imparts motion by the cog-wheels and shaft to the cog-wheel through which passes the feathered shaft mounted on the main carriage, and which in turn imparts the required motion to the drums for lifting the second carriage at the end of each complete motion of the main carriage.

4. Making the nut on the screw-leader in two parts, divided by a plane at right angles to the axis, when the two parts are attached together, so that they can be turned on each other, substantially as described, so that the threads can be set to any wear of the threads, and thus avoid end-play, as described.

5. Making the arbors of the two rollers with cylindrical bosses, to determine their distance apart, in combination with the mode of mounting them between boxes, and without interposed boxes, the said arbors being prevented from having end-play by means of V-shaped or curved fillets on the arbors fitted to corresponding cavities in the boxes, substantially as and for the purpose specified.

6. Mounting the bending-fingers in the sliding top plate, independent of and below the slide or carrier of the former, around which the teeth are bent, the said carrier being provided with an inclined plane or cam, acted upon by a like inclined plane or cam on the top plate of the fingers, substantially as described, so that as the fingers are drawn back the former shall be lifted up preparatory to its back motion, as fully set forth.
